UNITED STATES PATENT OFFICE

126,754

DESIGN FOR A TEXTILE FABRIC

Rose Faller, New York, N. Y.

Application March 20, 1941, Serial No. 99,720

Term of patent 3½ years

To all whom it may concern:

Be it known that I, Rose Faller, a citizen of the United States of America, residing in New York, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design. The dot and dash lines on the drawing show the design unit, which unit is repeated in staggered succession as indicated by the angles A and A'.

I claim:

The ornamental design for a textile fabric, as shown and described.

ROSE FALLER.
